UNITED STATES PATENT OFFICE.

JOHN WOOD AND WILLIAM ARMSTRONG, OF RAMSBOTTOM, ENGLAND.

APPARATUS FOR PRINTING MAGAZINES AND SUCH LIKE WORK.

1,261,885.

Specification of Letters Patent.

Patented Apr. 9, 1918.

Application filed February 16, 1915. Serial No. 8,498.

To all whom it may concern:

Be it known that we, JOHN WOOD and WILLIAM ARMSTRONG, subjects of the King of Great Britain and Ireland, residing at 5 Garden Engineering Works, Ramsbottom, in the county of Lancaster, England, have invented new and useful Improvements in Apparatus for Printing Magazines, and Such like Work, of which the following is 10 a specification.

This invention relates to a machine or apparatus for photogravure or intaglio printing whereby reproductions by photogravure processes can be obtained and printed 15 on one but usually on both sides of a passing web. Such processes are at present in use and need not be dealt with here, it being sufficient to say that two separate printing arrangements have been utilized 20 necessitating the paper traveling to some considerable extent in horizontal paths or paths inclined to the horizontal.

The object of our invention is to obtain an extremely compact machine or apparatus 25 for our purpose by combining in the one head or printing mechanism proper, both the two backing bowls and the two printing cylinders or rollers so that the same are adjacent to each other and located at one 30 end of the apparatus. In effect we use according to our system a duplex printing arrangement and have all the parts combined and grouped at one head and whereby the paper can pass to and fro in more or 35 less vertical or inclined paths instead of having horizontal or approximately horizontal travel.

In the machine or plant we prefer to employ a fluid cooled roller or rollers for 40 cooling the passing web or paper, which is an important feature in our proposed apparatus for duplex photogravure printing.

We also arrange to so carry the printing cylinders or rollers that same can be simultaneously adjusted or moved with respect 45 to the backing bowls over which the paper passes to be printed, or, alternatively, we arrange to adjust the backing bowls to the printing cylinders or rollers.

50 We will now proceed to clearly indicate the invention by a full description of one form of printing machine which will carry out our object, and which combines the features of novelty above indicated, and, in 55 this description, the attached drawings will be referred to.

In the said drawings:

Figure 1 shows a general side elevation of a single color duplex or perfecter photogravure printing machine of the type and 60 possessing the features indicated in the preamble.

Fig. 2 is a detail section of a water cooled roller which we prefer to employ.

Fig. 3 is an end view of Fig. 2.

Referring in particular to the construction illustrated generally in the attached drawing, we take the paper A to be printed from a batch or reel such as A' at one end of the apparatus and lead same upward to 70 drawing rollers a or such like, then down if necessary and over a saddle such as is marked b. From the saddle, the paper A preferably passes downward to a roller c and from thence it may pass in a horizontal 75 direction and over rollers d, e toward the printing mechanism to which it preferably passes upward from below. The actual printing combination comprises end frames f, f' in which are carried two sets of back- 80 ing bowls and printing cylinders or rollers, that is, a backing bowl and printing roller for each side of the paper. The backing bowl in the first set is marked g and the printing cylinder or roller h, while the back- 85 ing bowl of the second set is marked g' and the printing cylinder or roller h'. As shown, the two sets lie adjacent and are interconnected for driving and other purposes and this is preferably done by spur 90 wheels on shafts or studs carried by the end frames. The driving arrangement illustrated is a very simple one, and, consists of a main driving shaft i having a spur wheel i', said shaft having fast and loose 95 pulleys i" or being driven by gear. The spur wheel i' gears with a crown or spur wheel i" on the first impression bowl shaft and this wheel i" meshes with a spur wheel i" on the first printing cylinder or roller h 100 as is clearly shown. On the left of the spur wheel i' is an intermediate spur wheel j on the stud or other shaft j', and this intermediate spur wheel j gears into the crown or spur wheel j" on the second backing bowl 105 shaft, which crown or spur wheel j" gears into and drives the spur wheel j" on the second printing cylinder or roller h'.

The ascending paper A traveling over the roll e passes between the first backing bowl 110 g and printing roller h and is printed as to one face, and then goes upward and

travels around a revolving steam heated or drying cylinder such for example as the copper drying cylinder k . After passing around such cylinder, the paper is guided 5 around a provided cooling device and preferably is caused to contact with a revoluble water cooled roller l which contains water or has cooling liquid circulated therethrough. Such roller is very clearly illustrated in detail by Figs. 2 and 3 of the drawings. The hollow shafts $l' l'$ are supported by hollow brackets $l^2 l^2$, said shafts being properly packed by packing and glands as shown.

10 Water or cooling liquid enters at l^3 , passes through the hollow roller l and leaves at the outlet l^4 .

This roller l effects cooling of the paper, and, from that, the paper passes between 20 the second backing bowl g' and the second printing cylinder or roller h' . The drying cylinder and water cooled roller or rollers are most conveniently situated immediately above the duplex printing mechanism, as the 25 drawing shows, and can be easily supported by girders or framework. In connection with the second backing or impression bowl g' we use a traveling backing blanket m which passes over suitable guide rollers m' and is kept sufficiently taut by the tension 30 device m^2 .

After leaving the second printing elements, the paper is led upward over guide rollers and passes across suitable drying 35 sheets, chests, or the like to the cutting machine.

In order to have proper control over the printing mechanism we find it necessary to provide means to adjust or move the 40 printing cylinders or rollers and attendant parts and with this object in view we may use lever and link mechanism of a form which will give simultaneous adjustment of the two printing cylinders or rollers h, h' .

45 The form of lever and link mechanism shown in the drawing consists of a strong lower horizontal lever n fulcrumed at n' on a shaft supported in the frame and having short extension levers o to which links o' are connected at o^2 , these links o' being jointed at o^3 to second levers p pivoted to the frame at p' and which levers p have a nut and screwed spindles p^2 , which latter act on the bearing blocks of the first printing cylinder or roller h , and so movement 50 of the levers p effects movement of the first printing cylinder or roller h . To similarly influence the second printing cylinder or roller h' , we also utilize additional inclined or other levers q fulcrumed at q' and such 60 levers carry nuts for screwed adjusting spindles q^2 which act on the bearing blocks of the second printing cylinder or roller h' . The levers q are acted on and connected 65 by links r jointed to the short extensions

o influenced by the lower horizontal lever n . Adjustable weights s on this lower horizontal lever n keep the printing cylinders or rollers up to their work. To effect simultaneous lowering or adjustment of the 70 printing cylinders or rollers we provide a hand lever t pivoted at t' and having a cam t^2 , which cam acts on the lower horizontal lever n and raises the weighted end. It will be quite understood from the preceding 75 description of the lever and link mechanism that the requisite levers and links are duplicated at the other end of the machine supported by the frame and connected across as necessary.

80 Instead of the above described arrangement, or in addition thereto, we may arrange to be able to raise or lower the backing bows g, g' . We show an obvious way of doing this according to which the backing bowls are carried in adjustable bearings $g^x g'^x$ to which screwed spindles $u u$ are fitted and which work in the frame. Said screwed spindles are actuated by bevel gear v, v , as indicated, and the two sets of gear 85 may be interconnected so that adjustment of both bowls could take place simultaneously.

By directing the paper up and down, sagging does not take place, and correct 95 "register" is insured.

The whole construction makes for extreme compactness and efficiency and the entire printing mechanism is localized at 100 one point.

In case it is found that the ink can be dried very rapidly we may in some cases arrange to convey the paper after it has been printed by the first printing cylinder directly across to the second printing cylinder 105 without requiring to take the paper around the drying cylinder as hereinbefore described.

We declare that what we claim is:

1. A duplex or perfecter photogravure or 110 like printing machine, comprising a single head, single end frames, two impression bowls located in the one head, adjusting means for the bowls, two printing cylinders in the one head and mounted below the bowls, 115 lever and link mechanism to simultaneously move both printing cylinders, a paper supply source, guiding rollers for the paper, a stationary saddle, a drying cylinder arranged above the impression bowls, a water 120 cooling cylinder arranged between the drying cylinder and the impression bowls, and a positive driving connection between the impression bowls.

2. A duplex or perfecter photogravure or 125 like printing machine comprising a batch supporting means, draw rollers, a saddle, and guide rolls in combination with end frames supporting two impression bowls, printing cylinders below the bowls, sup- 130

ports therefor, adjusting devices for the cylinders comprising lever mechanism, a drying roller and additional guide rollers and a water cooled roller through which water is caused to flow, all in combination, and for the purpose set forth.

3. A duplex or perfecter photogravure or like printing machine comprising a single head, single end frames, two impression bowls supported by said end frames one above the other in relatively close relation, a positive drive connection between the bowls, two printing cylinders arranged one above the other for cooperation with the under surfaces of the impression bowls, means to movably support the cylinders, means for guiding the paper, and means for simultaneously adjusting both printing cylinders with relation to the impression bowls comprising a horizontal lever, a shaft on which the lever is fulcrumed, other levers

having linked connection with the aforesaid shaft and also having operative connection with the lowermost printing cylinder supporting means, an operating lever to actuate the first mentioned lever to raise and lower the lowermost printing cylinder, and link and lever connections between the first mentioned lever and the supporting means of the uppermost printing cylinder, whereby upon actuation of the operating lever both of the printing cylinders may be raised and lowered toward and away from the under surfaces of the impression bowls.

In testimony whereof we have signed our names to this specification in the presence of two subscribing witnesses.

JOHN WOOD.

WILLIAM ARMSTRONG.
